The ornamental design for an electric trolling motor control handle, as shown and described.

DESCRIPTION

FIG. 1 is a top plan view of an electric trolling motor control handle showing my new design;

FIG. 2 is a side elevation view thereof;

FIG. 3 is a bottom view thereof;

FIG. 4 is a left end view of the electric trolling motor control handle shown in FIG. 1;

FIG. 5 is a side elevation view opposite to the side shown in FIG. 2;

FIG. 6 is a right end view of the electric trolling motor control handle shown in FIG. 1; and,

FIG. 7 is a perspective view thereof shown in an extended position.

*FIG. 1**FIG. 2**FIG. 3*FIG. 4

FIG. 5

FIG. 6

FIG. 7
